UNITED STATES PATENT OFFICE.

EUGENE E. JONES, OF NEW YORK, N. Y.

DOOR-CHECK.

SPECIFICATION forming part of Letters Patent No. 658,916; dated October 2, 1906.

Application filed November 1, 1899. Serial No. 735,464. (No model.)

To all whom it may concern:

Be it known that I, EUGENE E. JONES, a citizen of the United States, residing at New York, in the county of New York and State of New York, have invented certain new and useful Improvements in Door-Checks, of which the following is a full and complete specification, such as will enable those skilled in the art to which it appertains to make and use the same.

10 This invention relates to door-checks of that type which are secured upon one face of the door near its lower edge, being downwardly projected by spring-pressure to frictionally engage the floor to hold the door at 15 any desired adjustment, and which are adapted to be raised out of contact with the floor and maintained in such raised position.

The object of the present invention is to produce a simple, cheap, readily-constructed, 20 and perfectly-operating device of this character which will be of few parts, in which there will not be, as in some devices of this character, the tendency of the parts to separate during operation, which may be speedily 25 raised or lowered from and into operative position by a movement of the foot, and which when raised will be maintained effectively in the raised position.

To this end my invention consists in the 30 novel construction and relative arrangement of the parts hereinafter fully described.

In the accompanying drawings, forming part of this specification, in which like letters of reference denote corresponding parts in the 35 several views, Figure 1 is an elevation of the lower part of a door carrying my improved door-check, which latter is shown in side elevation. Fig. 2 is a plan view of the lever forming part thereof. Fig. 3 is a side elevation of 40 the door-check removed from the door and seen from the inner face, or that which is in practice next adjacent to the door, the parts being shown in the position which they assume when the device is not in use. Fig. 4 45 is a plan view of the door-plate forming part of the device.

In the practice of my invention I construct a bracket or plate A, provided with two screw-holes a, through which it is secured to a door, 50 immediately above the lower edge thereof, by means of screws a'. Upon the outer face of

this plate A is a horizontal loop or block B, provided with a longitudinal slot b, passing vertically therethrough. Upon the end A' of the plate, which in practice is nearest to the hinge of the door, is a stud or post c, provided with a notch c'. At the opposite end of the plate A the edge thereof is formed into a curved bearing-face A², the projection of which increases upwardly to a certain point 60 and then decreases to form a notch or recess A³.

Pivoted mounted upon the plate A is a lever C, upon the upper surface of which is formed a rearwardly-curved segmental projection or hook D, which is passed upwardly through the loop B of the plate A from beneath, being of a diameter to work or slide longitudinally in the slot b of said loop and the rear or free end D' whereof ranges approximately parallel with the lever, so that this hook or projection serves positively to hold the lever from dropping out of the loop when the parts are in either the position shown in Fig. 1 or that shown in Fig. 3. The forward 75 end of the lever C, or that which is nearest to the free or latch portion of the door, is formed with a vertical recess d, in which is secured a rubber plug d'. The main body of the lever is longitudinally grooved in its under surface 80 to receive therein a spiral spring E, one end of which clasps the notched portion of the post c upon the plate A and the other end of which is connected with the lever B by engaging a cross-bar e, formed between two apertures e', 85 which extend vertically through the lever. The spring is of such length as to be extended in either position of the parts shown in Fig. 1 or Fig. 3, so that its normal tendency is to depress the forward end of the lever C and also 90 exert a longitudinal pull with respect thereto, whereby the hook D is held normally tight in the loop B. Upon the inner face of the forward end of the lever C is a projection C', approximately equal to the thickness of the plate A 95 and formed into a curved bearing-face C², which frictionally engages or rides upon the curved bearing-face A² of the plate A. The rear end C³ of the lever C is downwardly curved, and when the device is closed in the 100 position shown in Fig. 3 this end rests upon the post c.

The loop B and the post c are cast in one piece with the plate A, and the hook or projection D is similarly cast in one piece with the lever C, so that aside from the spring E 5 and the rubber plug d' the mechanism comprises but two parts.

The operation of my improved door-check will be readily understood from the foregoing description when taken in connection with 10 the accompanying drawings.

When the device is in position upon the door, as shown in Fig. 1, and the lower forward end of the lever C is depressed, whereby the plug d' engages or frictionally contacts with the floor, the tension or tendency 15 of the spring E to contract will maintain such frictional engagement and hold the door at any position or angle to which it may be opened. When it is desired slightly to open 20 the door, the foot is placed upon the rear end C³ of the lever and the same sufficiently depressed to raise the forward end of the lever, withdrawing the plug d' from engagement with the floor, and when the foot is removed 25 from this end C³ of the lever, after the door has reached the desired position, the forward end of the lever will again be depressed into operative engagement, as before. When it is desired entirely to release the door from 30 the action of the check, so that it may be freely opened and closed without hindrance, the end C³ of the lever is so far depressed by the foot as to bring the forward end slightly above the horizontal position, whereby the 35 line of tension of the spring will be passed and the pull thereof will be rearward and upward instead of rearward and downward, as previously. At the same time the curved bearing-face C² upon the projection C' of the 40 lever will engage the curved bearing-face A² upon the edge of the plate A, and as the face C² rides upon the upwardly-directed face A² there will be a slight longitudinal forward movement of the lever C and like tension of 45 the spring E until when the face C² has reached the inwardly-directed face A³ of the plate the spring will draw the lever an equally slight amount rearwardly, thereby effectually locking the lever in the raised 50 position. It is to be noted that the loose or longitudinally-slidable connection of the hook D with the loop B permits this movement of the lever and consequent locking in this manner.

Having fully described my invention, I claim as new and desire to secure by Letters Patent—

1. A door-check, comprising a plate adapted to be secured to the door and provided with 60 a bearing; a lever slidably mounted in said bearing whereby it is capable of slight longitudinal movement; a spring connected with the said lever and the said plate to normally depress the lever; locking means upon the 65 said lever and the said plate, whereby when the lever is raised in its slidable bearing to a certain position, the lever will be held in the

raised position through the tension of the spring.

2. A door-check, comprising a plate adapted to be secured to the door, a lever pivotally mounted therein, a spring connected with said lever and said plate to normally depress the lever, a curved bearing-face upon the forward edge of the door-plate or that nearest to 75 the holding end of the lever, said bearing-face being inwardly directed at the top, and a projection upon the lever adapted to ride upon said curved face, whereby when the lever is raised to a certain position, it will be 80 maintained in such raised position through the tension of the spring.

3. A door-check, comprising a plate adapted to be secured upon the door and provided with a bearing; a lever connected with said 85 plate and provided with an integral projection which positively engages the bearing to be thereby retained against detachment from the door-plate and which is longitudinally 90 slideable in said bearing; a spring connected with the said lever and with the door-plate whereby to maintain the lever normally depressed, and by which when the lever is raised, it is maintained in such raised position; the 95 said lever and the said plate being provided with bearing-faces adapted mutually to engage when the lever is raised.

4. A door-check, comprising a plate adapted to be secured to the door and provided with a projecting bearing upon its outer face which 100 is vertically slotted, a lever slidably mounted in said slotted bearing whereby it is capable of slight longitudinal movement; and a spring connected with the said lever and the said plate to normally depress the lever, and by 105 which when the lever is raised, it is maintained in such raised position.

5. A door-check, comprising a plate adapted to be secured to the door and provided with a slotted bearing; and a lever provided with 110 a curved projection hooked into said slotted bearing; and a spring connected with the said lever and the said plate.

6. A door-check, comprising a plate adapted to be secured to the door and provided with 115 a slotted block or loop upon the outer face thereof; a lever provided with an upwardly-projecting hook engaging said slotted block or loop and slidably mounted therein, whereby the lever is capable of slight longitudinal 120 movement; a spring connected with the said lever and said plate to normally depress the lever; the said plate and the said lever having mutually-engaging bearing-faces adapted to be interlocked by the spring when the lever is raised to a certain position.

In testimony that I claim the foregoing as my invention I have signed my name, in presence of the subscribing witnesses, this 31st day of October, 1899.
